(57) **CLAIM**

The ornamental design for the tray for use in ignition system for flammable material such as charcoal, as shown and described.

DESCRIPTION

The present design patent application is related to U.S. Design Patent Application No. 29/205,052, filed May 7, 2004, entitled “Ignition System For Flammable Material Such As Charcoal.”

FIG. 1 is a perspective view of a tray for use in an ignition system for flammable material such as charcoal according to the present invention;

FIG. 2 is a front elevational view of the tray of FIG. 1;

FIG. 3 is a back elevational view of the tray of FIG. 1;

FIG. 4 is a left elevational view of the tray of FIG. 1;

FIG. 5 is a right elevational view of the tray of FIG. 1;

FIG. 6 is a top plan view thereof; and,

FIG. 7 is a bottom plan view thereof.
